UNITED STATES PATENT OFFICE.

MALCOLM E. LAUNBRANCH, OF CHICAGO, ILLINOIS, ASSIGNOR TO WESTERN ELECTRIC COMPANY, OF CHICAGO, ILLINOIS, A CORPORATION OF ILLINOIS.

BLOCK-SIGNAL SYSTEM FOR ELECTRIC RAILWAYS.

No. 923,796.

Specification of Letters Patent.

Patented June 1, 1909.

Application filed December 14, 1905. Serial No. 291,671.

To all whom it may concern.

Be it known that I, MALCOLM E. LAUNBRANCH, citizen of the United States, residing at Chicago, in the county of Cook and State of Illinois, have invented a certain new and useful Improvement in Block-Signal Systems for Electric Railways, of which the following is a full, clear, concise, and exact description.

10 My invention relates to a block signal system, and its object is to provide an improved arrangement of apparatus and circuits which will be certain and reliable in operation.

15 My invention is especially adapted for use in connection with electric railways, and its purpose is to give the usual danger, caution and clear signals required for safety.

In the block signal systems in common use 20 a plurality of wires are required for connecting the apparatus at each end of the block. The greater number of wires the greater is the possibility of said wires becoming crossed, grounded or open, and thereby 25 interfering with the proper operation of the signals. In my invention there is such an arrangement of circuits and apparatus that but a single signaling wire is required between the blocks. The use of a single wire 30 permits the installation of a heavy, well insulated wire without excessive cost, and there is less likelihood of trouble arising from the signal circuit getting out of order. Moreover, by the arrangement of the circuits of 35 my invention, if a wire becomes crossed or opened, danger signals will be set at one or both ends of the block. The signals themselves, in my invention, may be either the usual semaphore and lamp signals at the 40 block stations or lamp signals in the cars. I consider the latter arrangement to be preferable, and will describe such an arrangement in connection with my invention, though I do not wish to be considered as 45 limiting myself to the use thereof. The usual trolley wire or third rail may be used to supply the source of power.

When the signals are placed upon the cars 50 an extra rail is provided at the points where the car enters and leaves the block, which rails serve as conductors to the signal apparatus on the car. By using these extra rails to be engaged by brushes on the car, a certain and more positive result is obtained than

where a switch is operated by the trolley wheel and a distant signal is to be watched.

In my invention the single wire connecting the signaling apparatus at each end of a given section of track, forms part of the circuit connected at one end of the block to a source of current and at the other to the ground. Included in this circuit are relay magnets, one at each end of the block, adapted to operate signals to indicate, upon a car entering the block, whether or not the block is already occupied by another car, and if so, in which direction it is traveling. If the block is clear, the car upon first entering operates mechanism to display a "clear" or safety signal. The car after entering operates a switch which through the apparatus at each end of the block will indicate a caution signal to a car following the first car and entering the block while the first car is therein, and a danger signal to the car entering at the other end of the block. As the car leaves the block it operates a switch which, if no other car is on the same block, will restore the apparatus to its normal condition.

I will describe my invention more particularly by reference to the accompanying drawing, in which,

Figure 1 is a diagram of the circuits and apparatus constituting my invention; Fig. 2 is a front elevation of step-by-step mechanism controlling the circuit of a solenoid employed in my invention; Fig. 3 is a side elevation of the same; and Fig. 4 is a transverse sectional view of said step-by-step mechanism.

For convenience of illustration I have shown the usual trolley wire as supplying the current for operating the signaling mechanism. The grounded connections are understood to be the track rail, as is usual in such cases.

The equipment consists of apparatus in the usual boxes situated near the ends of the block. In my invention the apparatus in these boxes is connected by means of a single wire *g* of low resistance, so that relays at either end can be shunted out from the other end. At the ends *A* and *B* of the block are insulated rails *j* and *j'*, respectively. The required length of these rails, in order that a signal may be displayed for a perceptible length of time, will depend upon the speed at which the cars are run. For all practical

purposes a short rail at the beginning and at the end of the block is sufficient. Switches C and C' which operate in both directions, are mounted a short distance inward from the beginning and end, respectively, of the block. Each switch is connected to the common source of current, and is adapted to be operated by a car entering or leaving the block, and thereby to be momentarily placed in contact with one or the other of the contact points. In their normal condition these switches are in the position shown in the drawing, between contact points 1 and 10 and 1^a and 10^a, respectively, of the signaling apparatus at each end of the block.

In normal condition a circuit is closed between the two signal boxes through wire g. This circuit may be traced as follows: from the line L through contact 8, relay h, contacts 7, 4, wire g, contacts 4^a, 7^a, relay h', and contact 8^a to ground. In this condition the armatures of relays h and h' are drawn up out of contact with points 13 and 13^a respectively, and rails j and j' have no electrical connection with the apparatus in said boxes. Each car may be provided with brushes M and N, adapted to engage the rails j and j', two relays O and P, and three lamps G, W and R, showing, when illuminated, green, white and red lights, respectively. Suppose, for example, that when a car enters the block at A there is no other car in the same block. The brushes M and N forming the contact terminals of the signal circuit carried by the car are electrically united by the rail j. A circuit is thus closed from the line L through the relay P, brush N, rail j, brush M, relay O, to ground. The relays O and P attract their armatures o and p, respectively; which engage contacts 16 and 17 and close a circuit from the line through armature p, contacts 17, 16, armature o, to ground, said circuit including lamp W. The lighting of this white light upon a car first entering the block is the signal that the block is clear. The white lamp W will stay lighted until the car reaches that point where it closes the switch C, whereupon said light will be extinguished and the green lamp G will be illuminated. When the switch C is operated by the car to engage contact 1, a circuit is closed from the line L, including a source of current, through relay d to ground. The relay d attracts its two armatures to close contacts 2 and 3 and to open contact 4. A circuit is thus closed from the line L through relay e, contacts 2, 5, 3, conductor g leading to apparatus at the other end B of the block, contacts 4^a, 7^a, relay h', contact 8^a to ground. The magnet e is thus energized and attracts its armature e^x, closing contact 6. At the same time the armature e^x opens contact 5, thereby opening the above described circuit through conductor g. The magnet h' is consequently de- energized and allows its armature to fall

against contact 13^a, and the rail j' is grounded through contacts 13^a and 14^a. The armature e^x also steps the disk i around one notch, moving the insulated part i' of the disk away from contact 9. A circuit is thus closed from the line through disk i, contact 9 and relay l to ground. When the car passes the switch C, and the contact which closed but momentarily is opened again, relay d becomes de-energized, and likewise magnet e, the armature e^x being retracted, and the disk i remaining in its advanced position. The relay l attracts its two armatures and closes contacts 12 and 15, and opens contact 7. The circuit through relay h being broken at contact 7, the armature of magnet h drops and closes contact 13. The rail j is thus connected to the line through contacts 13 and 15. Hence that terminal of relay P which was previously grounded through rail j is now also connected, through brush N, rail j, and contacts 13 and 15, to the line, and the relay P is therefore de-energized. The armature p drops back and opens the circuit of the lamp W at contacts 17, thereby extinguishing said lamp. The de-energization of relay P also permits its armature p' to fall back and close contact 18. Since the circuit from the line through contacts 15 and 13 to rail j is closed through relay O to ground, when the brush M engages said rail, said relay holds its armature o' against said contact point 19. A circuit is thus closed from the line through contact 18, lamp G, contact 19 to ground. It will thus be seen, as above stated, that at the same time the lamp W is extinguished, the green lamp G is lighted.

If after a car has entered at A, a second car attempts to enter at B its red lamp R will be lighted. This is due to the fact that the prior entering of a car at A grounded the rail j' through contacts 13^a and 14^a. When the brushes of the car entering at B engage with rail j' a circuit is closed from the line through relay P, brush N, rail j', and contacts 13^a, 14^a to ground, thus energizing said relay P. The relay O obviously is not energized, since the circuit therethrough is shunted by the low resistance path to ground from rail j' through the closed contacts 13^a, 14^a. The circuits including lamps W and G remain open therefore at contacts 16 and 19 respectively. The relay P attracts its armature p' which engages contact 20, thereby closing a circuit from the line through contact 20, lamp R, contact 21, to ground, lighting the red lamp R and thus indicating that there is a car already in the block coming from the opposite direction.

If after a car has entered the block at A a second car attempts to enter at A, its green lamp will first be lighted, thus indicating that there is a car ahead in the same block traveling in the same direction. This is due to the fact that, as above described, the rail

j is connected through contacts 13 and 15 to the line. When brushes M and N engage the rail *j*, relay P is not energized, as is apparent, but a circuit is closed from the line through 5 relay O to ground. The armature *o'* is attracted by the magnet O and engages contact 19, and a circuit from the line is closed through contact 18, lamp G, and contact 19 to ground. The lighting of lamp G prior to 10 the lighting of lamp W indicates that there is already a car in the block going in the same direction as the second car.

A car leaving the block at B when there is no other car in the block will place the signal 15 apparatus in its normal position. This is accomplished in the following manner: When the car leaves the block at B it operates the switch C', closing contact 10^a. A circuit is thus closed from conductor L to 20 ground through relay *q'*. Said relay attracts its armature and closes contact 11^a. A circuit is thus closed from the line through contact 11^a, relay *h'*, contacts 7^a, 4^a, 4, 12, and relay *r* to ground. The relay *r* operates 25 its armature *r'* to step disk *k*, and when the disk *k* has moved ahead as many steps as has the disk *i*, contact 9 will again rest on the insulated portion *i'* of disk *i*, thereby opening at this point the circuit through relay *l*. The armatures of said relay fall back, 30 opening contacts 12 and 15.

The step-by-step mechanism shown in Figs. 2, 3 and 4 is not an essential feature of my present invention, and other mechanism- 35 for accomplishing the same function may be substituted therefor. As shown in the drawings, the two disks *i* and *k* are mounted to rotate separately on a shaft *s* and are insulated from said shaft and from each other. 40 Each disk *i* and *k* has a toothed disk connected thereto, operated by the armatures *e'* and *r'*, respectively, to step said disks around. Normally the contact 9 carried by disk *k*, rests on the insulated portion *i'*. 45 The operation of the mechanism by a train entering a block steps the disk *i* forward and closes the circuit through the contact 9; when the disk *k* is operated by a car leaving the block and is moved ahead as many steps 50 as was the disk *i*, the contact 9 will obviously again rest on the insulated portion *i'*.

The contacts of switches C and C', as before stated, are time contacts, being made, for example, only for a few moments. It 55 will be seen, therefore, that upon the deenergization of relay *l*, brought about by a car leaving the block at B, if there is no other car in the block, the signal apparatus at both ends of the block will be restored to normal 60 position.

With the above described system, there being only a single wire *g* connecting the boxes, the probable trouble from crosses and open circuits etc. is reduced. However, if 65 wire *g* should become grounded, the relay *h'*

would be deenergized, since each of its terminals would then be connected to ground and contact 13^a would be closed so as to connect rail *j'* to ground, giving a danger signal at B. If the wire *g* becomes crossed with line L, rail *j* is thereby connected to ground and a danger signal will be given at A. If the wire *g* becomes open a danger signal will be given at both ends of the block. The relays *d* and *d'* are quick-acting relays, so that in the event of two cars entering at A and B toward each other almost simultaneously, the one first to enter will quickly operate the signal apparatus, and the second to enter will have its danger signal displayed. 70 75 80

What I claim is:

1. In a block signal system, the combination with a signal circuit leading from a source of current at one end of the block through a single wire only to ground at the other end of the block and including a magnet at each end of the block, of a switch contact associated with each magnet and adapted to be operated thereby, a circuit including signaling means and a source of current controlled by each contact, and means operated by a car entering or leaving a block to control the operation of the magnets. 85 90

2. In a block signal system, the combination with a normally closed signal circuit leading from a source of current at one end of the block through a single wire only to ground at the other end of the block, of an electromagnet at each end of the block included in said circuit, a switch arm associated with each magnet and adapted to be operated thereby, signals adapted to be controlled by said switch arm, and means operated by a car entering or leaving the block to control the character of the signals displayed 95 100 105 by the movement of the switch arm.

3. A block signaling system including a single wire only extending from one end of the block to the other, said wire being normally connected to a source of current at one end and grounded at the other, of an electromagnet at each end of the block having its windings in circuit with said wire, signals controlled by said electromagnets, a switch at each end of the block, and means operated 110 115 by the closing of the switch at either end of the block to deenergize said magnets and to operate said signals.

4. In a block signaling system, the combination with a normally closed circuit including a source of current and extending through a single signaling wire only from one end of the block to the other, of magnets *h*, *h'*, one at each end of the block included in said circuit, a switch at each end of the block, a magnet *d* energized upon the closing of one of said switches by a car entering the block, said magnet in its energization opening said circuit and thereby deenergizing the magnets *h*, *h'*, a local signaling circuit having a con- 120 125 130

tact closed by the deenergization of said magnet h' , said signaling circuit being arranged to be thereafter closed by a car entering the block at the end at which the magnet h' is located, and a local signaling circuit for the other end of the block controlled by the operation of the magnet d .

5. In a block signaling system, the combination with a normally closed electric circuit 10 extending through a single signaling wire only from one end of the block to the other, of a magnet at each end of the block included in said circuit, signals controlled by said magnets, a switch at one end of the block, 15 means operated when the switch is closed by a car entering the block to open said circuit and control signals at both ends of the block, a switch at the other end of the block, and means operated by the second switch when 20 closed by the car leaving the block to restore the signaling apparatus to its normal condition when the block is clear.

6. The combination with a track divided into blocks, and having at each end an insulated rail section, of a conductor connected to each rail section, each conductor including two switches, one normally closed to ground and the other normally open, apparatus at each end of the block electrically connected 25 by a single circuit extending from one end of the block to the other, said apparatus at each end including magnets adapted to control said switches, a switch at each end of the block adapted to be operated by a car entering or leaving the block to control the operation 30 of the signal circuit, so that a car upon entering an unoccupied block the rail section at that end is connected to a source of current and the rail section at the other end is 35 connected to ground, car-carried brushes adapted to engage the rail sections, and carried signals adapted to be operated by a circuit closed through the rail sections and 40 brushes.
- 45 7. In a block signaling system, the combination with a normally closed electrical circuit extending through a single signaling wire from one end of the block to the other, of magnets h h' included in said circuit, 50 one at each end of the block, a conductor connected to a rail at each end of the block, each conductor including two switches, one normally held open by said magnets and the other normally closed to ground, magnets 55 l l' , one at each end of the block, for actuating said second switches, a normally open

electric circuit for each of said magnets l l' , a switch at each end of the block adapted to be operated by a car entering or leaving the block, means actuated when the switch is 60 closed by a car entering the block to close the circuit of the magnet l at that end and to open the circuit between the two ends of the block, whereby the rail at the end of the block which the car enters is connected to a source of current and the rail at the other end is connected to ground, brushes carried by the car and adapted to engage with said rails, and a circuit including 65 signals carried by the car and connected to 70 said brushes, whereby appropriate signals are displayed when a car enters the block from either end.

8. A block signaling system including a single wire only extending from one end of 75 the block to the other, said wire being normally connected to a source of current at one end and grounded at the other, of an electromagnet at each end of the block having its windings in circuit with said wire, signals 80 controlled by said electromagnets, and means operated by a car entering or leaving a block at either end thereof to control the operation of said magnets.

9. In a block signal system, the combination with a circuit including a source of current and extending through a single signaling wire only from one end of a block to the other, of a magnet at each end of the block included in said circuit, signals included in a circuit carried by a car, said latter circuit being controlled by said magnets, and means operated by a car entering or leaving a block to control the operation of 90 said magnets.

10. In a block signal system, the combination with a circuit including a source of current and extending through a single signaling wire only from one end of a block to the other, of a magnet at each end of the block included in said circuit, and car-carried signals adapted to be controlled by said magnets upon a car entering the block, at either end thereof.

In witness whereof, I hereunto subscribe 105 my name this 1st day of September A. D., 1905.
